Attorney.

UNITED STATES PATENT OFFICE

107,774

DESIGN FOR A LIGHT CONTROLLING PLATE FOR LIGHTING FIXTURES

Edwin F. Guth, Webster Groves, Mo.

Application November 18, 1937, Serial No. 72,985

Term of patent 14 years

To all whom it may concern:

Be it known that I, Edwin F. Guth, a citizen of the United States and a resident of Webster Groves, St. Louis County, Missouri, have invented a new, original, and ornamental Design for a Light Controlling Plate for Lighting Fixtures, of which the following is a specification, reference being had to the accompanying drawing forming part thereof, in which

Fig. 1 is a plan view of a light-controlling plate for lighting fixtures, showing my new design;

Fig. 2 is a side elevation thereof; and

Fig. 3 is a cross-section thereof taken substantially along line 3—3 of Fig. 1.

The material of which the plate is formed is clear glass. Stippling is used in the drawing to indicate surfaces of the plate that are of frosted appearance. The absence of stippling indicates that the surface is clear and transparent.

I claim:

The ornamental design for a light-controlling plate for lighting fixtures, substantially as shown and described.

EDWIN F. GUTH.
